UNITED STATES PATENT OFFICE.

HENRY GEISENHÖNER, OF SCHENECTADY, NEW YORK, ASSIGNOR TO
GENERAL ELECTRIC COMPANY, A CORPORATION OF NEW YORK.

CUT-OUT.

No. 833,317.

Specification of Letters Patent.

Patented Oct. 16, 1906.

Application filed May 8, 1903. Serial No. 156,146.

To all whom it may concern:

Be it known that I, HENRY GEISENHÖNER, a citizen of the United States, residing at Schenectady, county of Schenectady, State of New York, have invented certain new and useful Improvements in Cut-Outs, of which the following is a specification.

The present invention relates to electric cut-out devices, and more particularly to pendent switches for use on incandescent-lamp and similar circuits.

As pendent switches have been constructed heretofore each switch has been provided with a single circuit-controlling means, so that where a plurality of lamps in a cluster or a chandelier were to be controlled by switches of this type it has been necessary either to connect the several lamps in series or to provide each of the lamps with an individual switch. The series arrangement is objectionable, for the reason that all the lamps in the series are necessarily lighted when only the light of one or two lamps is desired, and the arrangement of individual switches for the several lamps is objectionable on account of its unsightliness.

The object of my invention is to provide a single, compact, and neat-appearing pendent switch which shall be adapted to independently control a plurality of electric circuits.

The invention will be readily understood upon reference to the following description and the accompanying drawings, forming a part of this specification, in which—

Figure 1 is a side elevation of a pendent switch embodying one form of my invention. Fig. 2 is an axial section thereof. Fig. 3 is a top plan of the insulating-base and parts carried thereby. Fig. 4 is a perspective view of one of the retaining-plates. Fig. 5 is a detail view of a switch-plunger, and Fig. 6 is a top plan of the contact-plate.

The switch shown in the drawings comprises a two-part metallic shell A, an insulating-base B, inclosed thereby and supporting a plurality of spring-pressed circuit-closing devices C, adapted to be moved by hand into locking engagement with a contact-plate D, and a releasing device E, adapted when pressed to engage all the circuit-closing devices C that are in engagement with the contact-plate and disengage them therefrom.

The base B is made of porcelain, with a cy-

lindrical upper part 1, a hemispherical lower part 2 of less radial dimension than the cylindrical upper part, and an intermediate shoulder 3. A plurality of arms or projections 4 extend out from the cylindrical upper part 1 at equidistant points, and each is provided with a radial groove 5 of rectangular section for the reception of a circuit-closing device C. Intermediate the grooves 5 are other radial grooves 6 for the reception of the arms 7 of the contact-plate D. An axial aperture 8, having an intermediate contracted or shouldered portion 9, extends through the base B for the reception of the releasing device E.

The contact-plate D is made with a ring-shaped central portion, from the outer edge of which the radial arms 7 project and from the inner edge of which at points intermediate the radial arms 7 tongues 10 are bent up at an angle of about forty-five degrees. Each of the arms 7 is provided near its outer end with a screw-hole 11, the hole 11 in one arm receiving a binding-screw 12 for the common return-wire of all the circuits and the holes in the other arms receiving the securing-screws 13, which extend through the base parallel to its axis.

The circuit-closing devices C comprise short plungers each having a metallic rod 14, with a hooked head 14' at the inner end adapted when forced inward to engage a bent-up tongue 10 on the contact-plate D and screw-threaded at its other end into a metal plate 15 and the end of a prismatic bar 16, of insulation, of a size to loosely fit into a groove 5 in the base. The rods 14 are surrounded by helical springs 17, which impinge upon the metal plates 15 at one end and at the other upon the downturned ends 18 of the retaining-plates 19. Each of the retaining-plates 19 is provided with a T-shaped head provided at its opposite ends with screw-holes 20 for the reception of a securing-screw 21 and a binding-screw 22 for a lead-wire. The downturned ends 18 of the retaining-plates fit snugly in the inner ends of the grooves 5 and serve as stops for the inner ends of the spring 17 and for the hooked heads 14' in the outward travel of the circuit-closing devices C. The T-heads of the plates 19 span the grooves 5 and hold the circuit-closing devices therein.

The releasing device E comprises a metal

plunger 23, adapted to fit loosely in the contracted portion 9 of the axial aperture 8 in the base B, having its lower end screw-threaded to engage an insulating push-button 24, adapted to travel freely in the lower end of the aperture 8 against the tension of the helical spring 25, surrounding the plunger 23 between the contracted portion 9 and the end of the button 24, and its upper end provided with an enlarged cylindrical head 26, adapted when raised to engage the hooked heads 14 of the circuit-closing devices C and raise them free of the retaining-tongues 10 on the contact-plate D.

15 The inclosing shell A comprises a lower part 27, which fits upon the spherical surface of the face B and has at its upper edge segmental arms 28, between which the arms or projections 4 of the base project, and each of these arms 28 is provided with a spring-clip 29. The upper part 30 of the shell is made similar to the lower part with segmental arms 31, which pass between the arms 4 of the base and inside of the arms 28 of the lower part of the shell, and each of the arms 31 is provided with a shoulder 32 for engagement with a spring-clip 29. The upper part is provided with a lining 33 of fibrous insulation and a central bushing 34 of insulating material, whereby any exposed part of a lead-wire is prevented from coming in contact with the metal parts thereof.

I do not desire to restrict myself to the particular construction or arrangement of parts shown in the drawings, for it is apparent that they may be changed and modified without departing from the invention.

What I claim as new, and desire to secure by Letters Patent of the United States, is—

- 35 40 1. An electrical switch comprising a plurality of independent spring-pressed circuit-closing devices, a common contact-plate adapted to hold said devices in closed position against the tension of their springs, and 45 a releasing means common to all of said devices.
2. An electric switch comprising a plu-

rality of independent spring-pressed circuit-closing devices radially arranged about a common center, a common contact-plate adapted to hold said devices in closed position against the tension of their springs, and a concentrically - arranged releasing means common to all of said devices.

3. The combination of a base provided with radial arms or projections, and a two-part shell surrounding the body part of said base, each part of said shell having segmental projections from its edge with recesses between them for the reception of said radial arms or projections of the base, the segmental projections of one part having integral spring-clips and the projections of the other part having shoulders formed therein to interlock with said spring-clips.

4. The combination of a base provided with a radial channel, a terminal plate and a contact-plate secured to said base, a spring-pressed switch member located in said channel, and connected electrically with said terminal and adapted to be moved into locking engagement with said contact-plate and a releasing-plunger movable axially in said base and adapted to engage said switch member.

5. The combination of a base provided with a plurality of radial channels, a plurality of terminal plates secured adjacent said channels, a contact-plate secured to said base concentrically, a plurality of spring-pressed switch members located in said channels and adapted when pressed inwardly to lockingly engage said contact-plate and electrically connect it with the respective terminal plates, and an axially-movable releasing - plunger adapted to engage said switch members.

In witness whereof I have hereunto set my hand this 6th day of May, 1903.

HENRY GEISENHÖNER.
